CLAIM

The ornamental design for a slider bag, as shown and described.

DESCRIPTION

FIG. 1 is a top perspective view of the slider bag showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines shown in the drawings illustrate portions of the design that form no part of the claim. The dot-dash lines show unclaimed boundaries and form no part of the claim.

1 Claim, 6 Drawing Sheets
